(57) CLAIM

The ornamental design for a bottle opener, as shown and described.

DESCRIPTION

FIG. 1 is a top, front perspective view of the bottle opener of the present invention showing my new design;

FIG. 2 is a top plan view thereof;

FIG. 3 is a left side elevational view thereof;

FIG. 4 is a front elevational view thereof, the rear elevational view being a mirror image of the front elevational view;

FIG. 5 is a right side elevational view thereof; and,

FIG. 6 is a bottom plan view thereof.
